UNITED STATES PATENT OFFICE

CLARENCE R. MARTINEAU, OF ALBANY, NEW YORK

STARTER FOR AUTOMOBILE ENGINES

Application filed June 19, 1930. Serial No. 462,210.

This invention relates to means for starting the gas engine of an automobile.

The car is provided with a battery, which is connected to a starting motor. When the 5 motor is operated, it causes a pinion to engage a gear provided upon the crank-shaft of the engine, thereby rotating the crank-shaft, this mechanism being known as a Bendix drive gear; the pinion being self-10 engaging with the gear and also self-disengaging therefrom.

When the car is in use, the battery is being constantly recharged by means of a small dynamo which is always driven by the 15 engine. In warm weather, when the car is used for long drives, the battery is liable to become overcharged and injured, and its life is shortened. Moreover the battery, since it 20 must meet the exigency of starting a cold engine, has to be so large, heavy and costly as to be objectionable.

In cool weather, when the car is generally used only for short drives and the battery is frequently drawn upon to start the engine, 25 and also subjected to prolonged demand for current for the lights, the battery becomes depleted and injured, reducing its life.

It is a desideratum that the car be kept in an inexpensive unheated garage, usually 30 upon the premises of the owner of the car, and in cold weather the engine oil hardens and gums, and the engine is hard to start. In attempting to start the cold engine, the driver often draws heavily upon the battery that is 35 already partly exhausted, and in many cases is unable to start the engine, so that the battery becomes completely exhausted, and it becomes necessary to send it to a public garage to be recharged.

40 The object of the present improvements is to overcome the aforesaid difficulties, to reduce the size, weight and cost of the battery, and prolong its life, and also to overcome the difficulty of starting a cold engine in severe weather.

In order to obtain these results, I mount 45 in the car an auxiliary motor, which is independent of the car-battery, and is connected by a cable to any electric-light plug 50 in the wall of the garage. The auxiliary mo-

tor is of a type to be driven at high speed by an ordinary lighting current. This fast auxiliary motor is connected by movement-reducing gearing to the shaft of the main starting motor, so that said shaft is caused to 55 revolve, and its pinion is caused to mesh with the large gear provided upon the crank-shaft of the engine. Hence the engine may be started solely by the current coming in from the lighting main into the auxiliary engine, 60 without depleting the car-battery.

A switch may be provided upon the dashboard of the car for disconnecting the auxiliary motor as soon as the engine starts. The 65 cable of the auxiliary motor may be disconnectable from the electric-light plug in the garage.

If desired, the main motor may be driven simultaneously with the car-battery, thus 70 yoking the two motors for starting the engine in severest weather. The auxiliary motor may be capable, unaided, of starting the engine in weather that is not so severe.

After the engine has been started and the 75 car is driven out, the battery will be gradually recharged by the small dynamo usually provided upon the car. The engine will become warm, and the services of the auxiliary motor will be no longer required, since the main motor will be sufficient for starting the 80 warm engine. A one-way driving clutch is provided between the main motor and the auxiliary motor, to enable the main motor to be worked by the car-battery without operating the auxiliary motor.

85 Since no exigency or extraordinary demand is placed upon the battery when starting the cold engine, the battery may be reduced in size, weight and cost. Similar reduction can be made in the battery-charging 90 dynamo.

Heretofore it was the practice, when the car 95 was undergoing repairs, to start the engine and run it while the car stood in the garage, and this was found to be objectionable, because of the poisonous gas expelled from the engine, and also because the heating of the engine made the same difficult for the repairman to handle, and rendered him liable to become severely burned. According to the pres- 100

ent invention, it is only necessary to connect the auxiliary motor of the car to the electric-light plug in the wall of the garage, whereupon (the sparking switch being left open) 5 the engine may be driven for an indefinite period, at such speed as required by the repair-man, and without heating the engine.

Other features and advantages will hereinafter appear.

10 In the accompanying drawings or diagrams,

Figure 1 is a part-sectional plan of an automobile having an engine provided with the present improvements.

15 Figure 2 is a sectional elevation, illustrating the one-way driving connection between the main motor and the auxiliary motor.

20 Figure 3 is an elevation of a fragment of the dashboard, showing the stopping and starting switch for the auxiliary motor.

The engine 10 has a crank-shaft 11, upon which is provided the usual driving gear 12. This is operable by a pinion 13 of a Bendix starting gear of usual construction, controlled 25 by the usual floor-button 14. Said button closes a circuit 15 that includes the battery 16 and the main motor 17, whose shaft has a screw-device 18 for meshing the driving pinion 13 with the crank-shaft gear 12.

30 Spring 19 usually forms part of the Bendix drive.

The battery 16 is charged automatically by the usual means, not shown, but this battery in any car may be substantially reduced 35 in size as compared with the standard battery for that car. The battery does not need to have sufficient power and capacity to start the cold engine in severest weather, as heretofore, as the battery will rarely, if ever, be 40 called upon to start the motor when it is severely cold. The reduced size battery shown will be charged sufficiently during the running of the car to replenish such power as is consumed in starting the warm engine 45 for ordinary traffic. If the car is parked, the engine may remain warm for hours, so that the small battery will still suffice to start it under ordinary favorable condition of the ignition devices, etc.

50 In severest winter weather, when the oil is sluggish and the engine-mechanism is gummed, and works stiffly, the main motor 17 may not receive enough power from the battery 16 to start the engine with sufficient 55 speed. As a result the battery becomes more depleted from the unsuccessful attempts to crank the engine. The car-driver, however, may call into requisition an auxiliary motor 20, which is mounted upon the engine in the

60 same manner as is usual for the main motor 17. This auxiliary motor is connected by a wire 21 to a switch 22, mounted on the dash-board 23. An extension cable consisting of separable links 24, 25 (coupled at 26 by ordinary 65 plugs) carries at its free end an ordinary

wall-plug 27, for insertion into the light-socket which is usually provided in a garage. The part 25 may be regarded as an extension of the cable 24, so as to enable power to be obtained from any near-by house or store 70 when a car is parked, if necessary, in an emergency.

The connection 26 is easily separable by a pull on the cable 24, so that if the car should be started before disconnecting the wall-plug 27, the coupling 26 will separate, thus 75 avoiding any damage.

When the switch 22 is closed, the auxiliary motor 20, which revolves at very high speed, operates through its small pinion 28 to drive a large gear 29, the latter having a small pinion 30 meshing with a large gear 31 connected to the extended shaft 32 of the main motor 17. This movement-reducing gearing permits the use of an electric-light current 80 of low amperage from the motor to turn the pinion 13 at the requisite slower speed. The Bendix mechanism 13, 18, 19, therefore is operated by the motor 20 to connect up the latter to the gear 12, since said auxiliary motor 20 turns the shaft 32 which carries the usual 85 Bendix screw-device 18 for traversing the pinion 13.

When the switch 22 is turned to starting position, the button 14 may be concomitantly 90 operated to connect up the battery-circuit 15, 16, to drive the main motor 17, so that the motors may operate in tandem.

The gear 31 is connected to the shaft 32 by a one-way driving clutch 33, to enable the auxiliary motor 20 to drive the main motor-shaft 32, to permit said shaft 32 to revolve while the motor 20 remains stationary, when the car is out on the road.

When the car is undergoing repairs, the 100 plug 27 may be connected to a light-switch of the garage, and when required the engine may be operated slowly without becoming heated.

105 It will be perceived that the auxiliary motor may be plugged into the garage-lamp-socket to start the engine whenever it is desired to operate the car in warm weather as well as cold, and that this practice will materially conserve the power of the battery.

Variations may be resorted to within the 110 scope of the invention, and portions of the improvements may be used without others.

Having thus described my invention, I 115 claim:

1. The combination of an internal combustion engine for automobiles having a main engine-starting motor and shaft, a battery therefor, mechanism driven by said motor for starting said engine, and an auxiliary 120 motor connected to drive said starting mechanism, said auxiliary motor being of high-speed type to be operable by an ordinary lighting current; movement-reducing gearing forming a connection between the aux- 125 130

iliary motor and the shaft of the main starting motor.

2. The combination with an automobile internal combustion engine, of a starting device including a Bendix mechanism having a shaft, a high-speed motor operable by ordinary electric-light current and connected by movement-reducing gearing to said Bendix starter, said automobile having a battery, and a starting motor connected to said battery 10 to be operable thereby for starting the engine independently of the first-mentioned motor, said first-mentioned motor being capable of starting the engine independently of said battery.

15 3. In an automobile internal combustion engine, the combination of a main starting motor having a shaft for starting the engine, a battery for driving the motor, an auxiliary motor operable by ordinary electric-light current, and means connecting the auxiliary motor to said shaft of the main motor, to enable said motors to co-operate to start the engine, said auxiliary motor being connected to said shaft of said main motor by means of 20 a one-way driving clutch, to permit the main motor to rotate while the auxiliary motor is stationary.

4. In an automobile internal combustion engine, the combination of a main starting motor having a shaft for starting the engine, a battery for driving the motor, an auxiliary motor operable by ordinary electric-light current, and means connecting the auxiliary motor to said shaft of the main motor, to enable 30 said motors to co-operate to start the engine, said connecting means including movement-reducing gearing between said auxiliary motor and said shaft of said main motor.

35 5. In an automobile internal combustion engine, the combination of a main starting motor having a shaft for starting the engine, a battery for driving the motor, an auxiliary motor operable by ordinary electric-light current, and means connecting the auxiliary motor to said shaft of the main motor, to enable said motors to co-operate to start the engine, said auxiliary motor having a 40 small pinion, a large gear meshing with said pinion, a second small pinion connected to 45 said large gear, and a second large gear upon said shaft of the main motor.

CLARENCE R. MARTINEAU.
